GAS CONTROLLING DEVICE

Alphonse A. Heinzemann, Rockville Centre, N. Y., assignor to Bludalk, Inc., New York, N. Y., a corporation of New York

Application February 15, 1937, Serial No. 125,789.

9 Claims. (Cl. 137—152)

My invention relates to gas controlling devices and refers particularly to devices adapted for the control of gas mixtures introduced into internal combustion engines by means for automatically maintaining a practically constant vacuum in the intake manifold during deceleration irrespective of the speed of the engine.

When the speed of an internal combustion engine is decelerated, and especially when it is suddenly decelerated, by releasing the accelerator, the engine is rotating at a speed greater than its idling speed as it functions as a brake during this period of deceleration and hence, with the throttle closed, the vacuum in the intake manifold is greater than the vacuum at idling speed and this increased vacuum draws in a greater amount of gasoline than can be completely burned in the engine.

As a result of this over-feed of gasoline, the exhaust gases contain a large amount of unconsumed, or partially consumed, gases which have an irritating and obnoxious odor.

This undesirable effect is particularly noticeable in the case of large heavy vehicles such as trucks and busses.

The object of my invention is devices which will automatically control this vacuum during deceleration and maintain it at a practically uniform vacuum, thus preventing the feed of gasoline beyond the consuming capability of the engine during this period, and hence, obviating the production of obnoxious gases.

The novelty and effectiveness of my device will be evident upon a consideration of my specification and the accompanying drawing, in which similar parts are designated by similar numerals.

In the accompanying drawing illustrating one form of a device of my invention,

Figure 1 is a section through the line 1—1 of Figure 2.

Figure 2 is a vertical cross-section through the line 2—2 of Figure 1.

Figure 3 is a section through the line 3—3 of Figure 1.

Figure 4 is a section through the line 4—4 of Figure 1.

The particular form of my device shown in the accompanying drawing comprises a casing having the top member 10, the bottom member 11, the side members 12 and 13 and the end members 14 and 15. The top member 10 is extended into the enlarged portion 16 having a central opening 17 and the two smaller openings 18, 19.

A bore, or air-intake chamber, 19 extends

through the casing from the end member 15 into the opening 17 of the member 16.

A bore, or vacuum chamber, 20 extends through the casing from a recess in the end member 15 and enters bore 19 through the passage 21. It will thus be seen that both bores, or chambers, 19 and 20 are connected with the opening 17 of the member 16.

Within the vacuum chamber 20 there is a slideable piston 22 having a threaded central opening 23 and a separate slideable member 24. A coil spring 25 is positioned within the chamber between the member 24 and the opposite end wall 26 of the chamber. The revolution of the threaded bolt 27 will move the member 24 and hence, will control the resilient force of the spring 25.

A cap 30, having an opening 31 into the portion 32 of the chamber 20 to allow of the admission or exit of air during the movement of the piston 22, is affixed to the end 15 by means of threaded bolts 33, 33.

The piston 22 carries a pin 34 extending through the elongated opening 35 in the top member 10. The top member 10 carries the extended threaded member 36 and has an annular opening 40 into the air chamber 19.

Positioned upon the top member 10 is a disk member, or revoluble valve, 37, having a central opening through which the threaded bolt 36 extends and which acts as an axis for the revolution of the valve 37.

This disk also has an elongated opening 38 through which the pin 34 of the piston 22 extends, the opening 38 being positioned angularly with respect to the opening 35 of the top 10 for purposes described later. The disk 37 has also an annular opening 39.

It will thus be seen that when the device is in the position shown in the drawing, the openings 39 and 40 will not be in alignment and the opening 40 will be covered by the valve 37. The movement of the piston 22 inwardly toward the spring 25 will cause the pin 34 to move along the openings 35 and 38, thus revolving the valve 37 and causing the opening 39 to gradually approach the opening 40 and become aligned therewith.

Positioned over the valve 37 is a cap 41 having a plurality of openings 42, 42 therein, the cap 50 being maintained in position by means of the internally threaded boss 43 and the threaded pin 36, a rotatable coil spring 44 being positioned between the boss 43 of the cap 41 and the boss 45 of the disk 37.

The operation of the device is as follows:

The member 16 is placed between the flange 50 of the carburetor manifold 51 and the flange 52 of the air intake manifold 53 and attached thereto by means of bolts passing through the openings 18, 18 of the member 16 and corresponding openings through the flanges 50 and 52.

The engine is allowed to run at idling speed and the position of the piston 22 is adjusted by means of the threaded bolt 27 so that the opening 39 of the valve 37 is close to the edge of the opening 40 of the top 10, retaining, however, the opening 40 in closed condition.

In this position, the engine is at its greatest vacuum, except when the vehicle is decelerating, and vacuum in the intake manifold 53 is transmitted to piston 22 through air passage 19 and passage 21 to the vacuum chamber 20.

When the speed is decelerated, the vacuum increases, the piston 22 is drawn inwardly toward the spring 25, causing the pin 34 to move inwardly resulting in a revolution of the valve 37 and a gradual opening of the opening 40 and allowing air to be drawn through the openings 42, 42, the openings 39 and 40 into the air chamber 19, which being connected with the intake manifold 53 reduces the vacuum and tends to maintain it at the idling speed vacuum.

In other devices designed for the purpose of eliminating fumes, the employed valve is held on its seat by the usually employed spring valve, that is, by means of a spring fixedly attached to the valve stem. It is obvious that in spring loaded valves of this construction the spring tension on the valve must approximately equal the vacuum pull on the valve head, and hence the valve is held very lightly upon the seat, permitting air to leak into the intake manifold tending toward irregular running of the engine at idling speed.

This defect is overcome in my device in which the vacuum tends to hold the rotating valve 37 against the casing at all speeds except when the two openings 39 and 40 are in complete alignment and the opening 40 entirely open, in which position the vacuum is materially reduced and the valve 37 is free to return to its normal position.

It will thus be seen that my device is adapted to maintain a practically uniform vacuum in an internal engine during deceleration irrespective of its speed and to thus maintain a combustion, or explosive, mixture commensurate with the ability of the engine to consume, or ignite, it, thus preventing the exhaust discharge of objectionable and irritating gas mixtures of unconsumed or partially consumed gases.

I do not limit myself to the particular size, shape, number, arrangement or material of parts as shown and described as these are given solely for the purpose of clearly describing my invention.

What I claim is:

1. A gas controlling device comprising a casing; an air chamber within said casing opening outwardly therefrom; a vacuum chamber within said casing opening outwardly therefrom, said casing having a port opening outwardly from said air chamber; a revoluble valve abuttable upon said casing having a port therethrough and so positioned that the revolution of the valve will move the two said ports into and out of alignment with each other said elements being so positioned with respect to each other that a vacuum in said vacuum chamber will maintain said revoluble valve upon said casing during all per-

iods of operation except when the said ports are in complete alignment; and vacuum movable means within the vacuum chamber, the movement of which will revolve said valve.

2. A gas controlling device comprising a casing; an air chamber within said casing opening outwardly therefrom; a vacuum chamber within said casing opening outwardly therefrom, said casing having a port opening outwardly from said air chamber; a conduit connecting said air chamber and said vacuum chamber; a revoluble valve having a port therethrough and so positioned that the revolution of the valve will move the two said ports into and out of alignment with each other said elements being so positioned with respect to each other that a vacuum in said vacuum chamber will maintain said revoluble valve upon said casing during all periods of operation except when the said ports are in complete alignment; and spring controlled vacuum movable means within the vacuum chamber, the movement of which will revolve said valve.

3. A gas controlling device comprising a casing; an air chamber within said casing opening outwardly therefrom; a vacuum chamber within said casing opening outwardly therefrom, said casing having a port opening outwardly from said air chamber; said casing having an elongated opening therethrough and an extended pin; a revoluble valve abuttable upon said casing having a port, a centrally positioned opening through which said pin extends and an elongated opening therethrough, said valve being so positioned that its revolution around said casing pin will move the two said ports into and out of alignment with each other, said elements being so positioned with respect to each other that a vacuum in said vacuum chamber will maintain said revoluble valve upon said casing during all periods of operation except when the said ports are in complete alignment; vacuum movable means within the vacuum chamber; and an extended pin carried by said vacuum movable means and extending through said two elongated openings, the movement of said vacuum movable pin revolving said valve.

4. A gas controlling device comprising a casing; an air chamber within said casing opening outwardly therefrom; a vacuum chamber within said casing opening outwardly therefrom, said casing having a port opening outwardly from said air chamber; a revoluble valve having a port therethrough and so positioned that the revolution of the valve will move the two said ports into and out of alignment with each other, said elements being so positioned with respect to each other that a vacuum in said vacuum chamber will maintain said revoluble valve upon said casing during all periods of operation except when the said ports are in complete alignment; and vacuum movable means within the vacuum chamber, the movement of which will revolve said valve.

5. A gas controlling device comprising a casing; an air chamber within said casing opening outwardly therefrom; a vacuum chamber within said casing opening outwardly therefrom, said casing having a port opening outwardly from said air chamber; a conduit connecting said air chamber and said vacuum chamber; a revoluble valve having a port therethrough and so positioned that the revolution of the valve will move the two said ports into and out of alignment with each other, said elements being so positioned with respect to each other that a vacuum in said

vacuum chamber will maintain said revoluble valve upon said casing during all periods of operation except when the said ports are in complete alignment; and vacuum movable means within the vacuum chamber, the movement of which will revolve said valve.

5 6. A gas controlling device comprising a casing; an air chamber within said casing opening outwardly therefrom; a vacuum chamber within 10 said casing opening outwardly therefrom, said casing having a port opening outwardly from said air chamber; a revoluble valve having a port therethrough and so positioned that the revolution of the valve will move the two said ports into and out of alignment with each other, said elements being so positioned with respect to each other that a vacuum in said vacuum chamber will maintain said revoluble valve upon said casing during all periods of operation except when 15 20 the said ports are in complete alignment; and spring controlled vacuum movable means within the vacuum chamber, the movement of which will revolve said valve.

7. A gas controlling device comprising a casing; an air chamber within said casing opening outwardly therefrom; a vacuum chamber within 25 said casing opening outwardly therefrom, said casing having a port opening outwardly from said air chamber; a conduit connecting said air 30 chamber and said vacuum chamber; a revoluble valve abuttable upon said casing having a port therethrough and so positioned that the revolution of the valve will move the two said ports into and out of alignment with each other, said elements being so positioned with respect to each other that a vacuum in said vacuum chamber will maintain said revoluble valve upon said casing during all periods of operation except when 35 the said ports are in complete alignment; and vacuum movable means within the vacuum chamber, the movement of which will revolve said valve.

8. A gas controlling device comprising a casing; an air chamber within said casing opening outwardly therefrom; a vacuum chamber within 40 said casing opening outwardly therefrom, said casing having a port opening outwardly from 45

said air chamber; said casing having an elongated opening therethrough and an extended pin; a revoluble valve abuttable upon said casing having a port, a centrally positioned opening through which said pin extends and an elongated opening therethrough, said valve being so positioned that its revolution around said casing pin will move the two said ports into and out of alignment with each other, said elements being so positioned with respect to each other that a vacuum in said vacuum chamber will maintain said revoluble valve upon said casing during all periods of operation except when the said ports are in complete alignment; spring controlled vacuum movable means within the vacuum chamber; and an extended pin carried by said vacuum movable means and extending through said two elongated openings, the movement of said vacuum movable pin revolving said valve.

9. A gas controlling device comprising a casing; an air chamber within said casing opening outwardly therefrom; a vacuum chamber within 25 said casing opening outwardly therefrom, said casing having a port opening outwardly from said air chamber; a conduit connecting said air chamber and said vacuum chamber; said casing having an elongated opening therethrough and an extended pin; a revoluble valve abuttable upon 30 said casing having a port, a centrally positioned opening through which said pin extends and an elongated opening therethrough, said valve being so positioned that its revolution around said casing pin will move the two said ports into and out of alignment with each other, said elements being so positioned with respect to each other that a vacuum in said vacuum chamber will maintain said revoluble valve upon said casing during all periods of operation except when the said ports are in complete alignment; spring 35 controlled vacuum movable means within the vacuum chamber; and an extended pin carried by said vacuum movable means and extending through said two elongated openings, the movement of said vacuum movable pin revolving said 40 valve.

ALPHONSE A. HEINZELMANN.
